United States Patent Office.

OLIVER C. SWEET, OF ALBANY, NEW YORK.

Letters Patent No. 32,564, dated September 29, 1868; antedated September 24, 1868.

IMPROVEMENT IN MACHINE FOR DRYING AND STRETCHING FABRICS.

The Schedule referred to in these Letters Patent and making part of the same.

TO ALL WHOM IT MAY CONCERN:

Be it known that I, OLIVER C. SWEET, of Albany, in the county of Albany, and State of New York, have invented a new and improved Apparatus for Stretching and Drying Tubular Fabric; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my improved drying-apparatus.

Figure 2 is a side elevation of the stretcher.

Figure 3 is a side elevation of the winding-up device and stretcher.

Figure 4 is a vertical transverse section of the same.

Figure 5 is a vertical transverse section of the drying-apparatus, the plane of section being indicated by the line z z , fig. 1.

Similar letters of reference indicate corresponding parts.

This invention relates to a new apparatus for drying and stretching tubular fabric, and is more particularly intended for the treatment of tubular knit fabric.

The invention consists in the use of a fixed or expandable horizontal drying-frame, upon which the fabric can be drawn and stretched, to be exposed to the air for drying.

The invention also consists in the arrangement of a stretching-device, upon which the fabric is spread, to be fed, in a flattened shape, to the winding-up or calender-rollers, after it has been dried on the frame.

A represents a horizontal bar, hinged, at one end, to a stationary frame or wall, B, so that it can swing sideways.

C represents a horizontal bar, suspended, by means of three or more tongs, D D, from a horizontal stationary beam or bar, E.

The tongs consist each of two bars, a a , hinged together, each bar having a hook at its lower ends, so that the bar C can rest upon the hooks when suspended.

The upper ends of the bars a a are secured to strings, b b , which are fastened to the beam E. Thus the jaws of the tongs are kept closed by their own weight, and by that of the bar C. The bar C may be made of metal, in the shape of an inverted letter U, or of wood, and to the lower or inner side of the bar C are hinged two or more toggle-levers, F F, which carry another horizontal bar, G, of similar shape to the bar C, as shown in fig. 5.

The joints of the various toggle-levers are connected by means of a horizontal bar, c, whereby their simultaneous operation is secured.

Between the bars C and G are also arranged levers, d d, one end of one lever being hinged to the bar C, and one end of the other to the bar G, the hinges being opposite to each other, the bars crossing each other, and working on a pin or point at the point of crossing, and reaching to the opposite bar G or C, and sliding on the inner edge of the same, as shown in fig. 1.

These levers d d insure greater uniformity of motion and steadiness to the drying-frame, and prevent a lateral motion of the bars when they are being opened or closed. They also keep the ends of the toggles opposite each other, and cause these ends to move in a direction perpendicular to the opposite bars, respectively. To the lower bar G is secured one end of a cord or chain, e, which passes under the bar C, and over friction-rollers f, or their equivalent, as shown in fig. 1.

The other end of the cord e is wound round a drum, H, having a ratchet-wheel and pawl, as shown, so that, when the drum is revolved, by means of a crank or other device, the cord will be wound up, raising the bar G towards the bar C, while, when the pawl is raised, the cord will be unwound, allowing the bar G to be lowered.

The fabric to be dried is drawn upon the bar A, and then the ends of the bars A and C are connected, as shown in fig. 1, they being arranged so that they can be united.

The bar G is then raised as far as practicable, and the fabric is drawn upon the drying-frame C G until it comes against the first tongs D.

The first tongs is then detached from the bar C, and the fabric is drawn to the second tongs. The first tongs is then attached to the frame, and the second detached, and thus the fabric is drawn over the entire length of the frame C G.

When the required quantity of the fabric is drawn upon the drying-frame, the bar G is lowered, and thus the fabric is stretched, so that the air can freely pass through it, to dry the same.

The toggle-levers are made adjustable, so that the frame can be stretched to suit fabrics of any diameter.

When the fabric on the frame is dry, it can be drawn off the bar C upon a vertical post I, as shown, and, when a whole piece of dried fabric has been thus transferred to the post I, the latter is removed and fastened to the stretcher K.

The stretcher consists of two vertical bars, g g, hinged, by means of levers h h, to a sleeve, i, sliding upon a central vertical rod, j, as shown in fig. 2. The rod j is fitted upon the post I, and then the fabric can be drawn off the post i, and over the stretcher, to the rollers.

The bars g g are provided with pulleys, l l, over which pass endless friction-cords, m m, so that the fabric will not work against the edges of the bar, nor rub against the same, but will, while being drawn up, carry the friction-cords along, thus avoiding friction between the spreader and the fabric, and carrying the cloth without stretching it.

The stretcher is placed under a suitable set of rollers, J J, upon which the fabric is wound, or where the same is calendered, and then wound up, as may be desired.

The rollers may be made adjustable, so that the upper roller n rests upon the fabric, and presses the same upon the lower roller o, while it passes to the winding-up roller p. The rollers n and o may be hollow or solid, as may be desired.

Having thus described my invention, what I claim as new, and desire to secure by Letters Patent, is—

1. The adjustable drying-frame C G, suspended, by means of removable tongs D D, from a suitable stationary bearing, and made contractible or expandible, at will, substantially as herein shown and described.
2. The hinged adjustable drying-frame C G, arranged as described, in combination with the swinging receiving-bar A, substantially as herein shown and described.
3. The rollers l and cords m, arranged as described, in combination with the bars g, standard I j, sleeve i, and arms h, for the purpose specified.
4. The stretcher-frame C G, when arranged as described, in combination with the tongs D D, bar A, post I, and stretcher K, all made and operating substantially as herein shown and described.
